UNITED STATES PATENT OFFICE.

CHARLES A. SPOONER, OF PHILADELPHIA, PENNSYLVANIA.

APPARATUS FOR SUPPORTING ROLLER-SKATERS IN RINKS.

No. 895,055.

Specification of Letters Patent.

Patented Aug. 4, 1908.

Application filed August 22, 1907. Serial No. 389,661.

To all whom it may concern:

Be it known that I, CHARLES A. SPOONER, a citizen of the United States, residing at the city of Philadelphia, in the county of Philadelphia, and State of Pennsylvania, have invented certain new and useful Improvements in Apparatus for Supporting Roller-Skaters in Rinks, of which the following is a specification.

10 My invention has relation to an apparatus for supporting roller skaters in rinks; and in such connection it relates more particularly to the construction and arrangement of an elevated course or trackway and to means 15 carried by and suspended from said track for supporting the roller skaters.

The principal objects of my invention are first, to provide an apparatus to permit persons to learn with ease and without danger to 20 limb the art of roller-skating; and second, to provide for such purpose an apparatus with an elevated track or course upon which are adapted to travel a series of trucks or carriers from which supporting means for persons are suspended and with a yielding device spanning each end of each of the trucks and projecting therefrom, and the yielding devices of two trucks adapted to permit of 25 contacting with each other at a point in the central longitudinal axis of the trucks as well as at points sidewise to such axis to prevent collision between skaters.

The nature and scope of my invention will be more fully understood from the following 35 description taken in connection with the accompanying drawings forming part hereof, in which

Figure 1 is a view, illustrating in side elevation an elevated course or trackway, auxiliary tracks connected with the main trackway by switches and trucks or carriers having buffers or fenders projecting therefrom and means suspended from the trucks for supporting skaters. Fig. 2 is a top or plan 45 view of the track or course and a series of auxiliary tracks. Fig. 3 is a detail view, enlarged, illustrating partly in section and partly in side elevation the track or course, a truck or carrier running on the track, and a 50 spring controlled drum for automatically elevating the suspended supporting means. Fig. 4 is a top or plan view of the track or course and truck or carrier of Fig. 3; and Fig. 5 is a detail view, still further enlarged, illustrating partly in vertical central section and

partly in side elevation; the track and the truck or carrier shown in Fig. 3.

Referring to the drawings 6, is a preferably oblong course or track, which by means of hangers 8, is suspended from the ceiling 9, or other portion of a building, not shown. Preferably at one side of the trackway 6, are arranged a series of auxiliary tracks 10, which by means of switches 11, arranged in the main trackway 6, and by switches 12, arranged adjacent thereto, and forming the continuation of the outermost of the auxiliary tracks 10, are connected with the main trackway 6, and the latter with all of the auxiliary tracks 10, as will be readily understood from Fig. 2.

Upon the main trackway 6, and auxiliary tracks 10, are adapted to travel a series of trucks or carriers 14, each consisting of a frame 15, bent at the upper end into a U-shape to receive the shafts 16, of flanged supporting-wheels 18, which are substantially surrounded by the frame 15. In addition to the supporting-wheels 18, the frame 15, is provided with flanged guide-wheels 19, engaging the underside of the track 6, and thus holding the supporting-wheels 18, and by the same the frame 15, at all times in engagement with the same. The trucks 14, so formed serve to carry supporting means 17, each, consisting of a housing 20, secured to the frame 15, and arranged below the guide-wheels 19, which serve in conjunction with the frame 15, to support a shaft 21, upon which is mounted a drum 22, connected with the shaft 21, by a spiral spring 23, as shown in Fig. 3. The drum 22, serves to support a chain 24, which is held wound upon the same by the spiral spring 23, and for a certain portion of the length is concealed in the housing 20, for the purpose of normally holding rings 25, belts 26 or bars 28, secured to the free end of the chain 24, and extending beyond the housing 20, into a position to clear the heads of skaters or other persons passing beneath the same. However, the height in which the rings 25, belts 26 or bars 28, are held is such as to be still in easy reach of the hands of persons, which by taking hold of the rings or bars lower the same for a proper length by unwinding the chain 24, from the drum 22, against the tension of the spring 23. Persons desirous of learning the art of roller-skating by means of the trucks 14, and supporting means 17, suspended

therefrom will be prevented from falling on the floor 7, of the skating-rink, when losing their balance on the roller skates, and will thus be protected against injury. Moreover, 5 the truck 14, and supporting means 17, will steady and more or less support the skaters during the time of acquiring the necessary skill to skate without the aid of the same. In order to permit of the free use of the hands 10 of the skater during skating the same can be connected with the chain 24, by the belt 26, which is applied to the body of the skater and is connected to the chain by straps 27. The skaters by their forward movement will 15 move the truck 14, supporting the same along the trackway 6, and if desirous of leaving this trackway by the actuation of one of the switches 11, arranged in the main trackway 6, can move the truck 14, supporting the 20 same upon the outermost of the auxiliary tracks 10, or by the additional actuation of the switches 12, upon any of the auxiliary tracks 10, arranged intermediate of the outermost track 10, and trackway 6. On the auxiliary tracks 10, the skater can take a rest 25 and remain for any time desired free from the bodies of skaters using the main trackway 6. From the auxiliary tracks 10, the skater may again reach the main trackway by the proper 30 actuation of the switches 11 and 12. At the same time the auxiliary tracks 10, may be used as the starting point from which the skaters are switched upon the main trackway 6.

35 The distance of the supporting-wheels 18 and guide-wheels 19, of the trucks 14, from each other, and the arrangement of the supporting means 17, suspended therefrom, in the vertical central axis of the tracks 6 and 40 10, prevents any possible binding of the trucks 14 on the tracks. Furthermore, to prevent collision of skaters with each other, and to hold the same at all times a defined distance apart, each of the trucks 14, is 45 provided with buffers or fenders 30, projecting from each end thereof. The buffers 30, preferably, consist of a strip of metal, the ends of which are suitably secured to projections 29, of the frame 15, of the trucks 50 14. These so formed buffers at each end of a truck 14, are yielding and so bent or curved as to insure the contacting of the same with the buffer of an adjacent truck in the longitudinal central axis of said trucks as well as 55 at points sidewise to such axis upon sharp

curves of the main track 6, as well as auxiliary tracks 10.

The provision of buffer devices 30, of the character defined, and arranged so as to project from each end of a truck, enables 60 shock when two such buffer devices come in contact with each other to be appreciably lessened. This is due to the fact that whether the contact be direct, that is, in a plane longitudinally of the central axis 65 through the trucks, or to either side of such plane, thud or jar is relieved by reason of the yielding character of both bow-shaped buffer devices 30 of the trucks. In practice it is highly desirable in the use of trucks of the 70 type explained, for roller skating purposes to be able to support the roller skating beginners particularly suspended therefrom against the possibility of being unable to control the speed of travel of the supporting 75 devices and should they contact violently, such is quite apt to disarrange or derail the same and thereby to cause bodily harm, which is entirely obviated by the respective 80 shiftings by contact of the buffer devices 30, in such cases with two trucks. At the same time the main track 6, by proper actuation 85 of the switches 11 and 12, may be extended by the outermost of the auxiliary tracks 10, or by any of the auxiliary tracks intermediate 90 of the outermost track 10, and main trackway 6.

Having thus described the nature and objects of my invention what I claim as new and desire to secure by Letters Patent is:—

90

An apparatus of the character described, comprising a track, trucks supported by the track, supporting means suspended from the trucks, and a bow-shape spring device secured at its extremities to each end of each 95 truck, the bows of which devices project from the ends of said trucks, said spring devices of two trucks being capable of side- 100 wise displacement with respect to the trucks and permitting contact with each other at a point in the central longitudinal axis of the trucks as well as at points sidewise to such axis.

In witness whereof, I have hereunto set my signature in the presence of two sub- 105 scribing witnesses.

CHARLES A. SPOONER.
